UNITED STATES PATENT OFFICE.

OLIVER E. HARRIS, OF ABINGDON, ILLINOIS.

ROTARY CHURN.

1,170,251.

Specification of Letters Patent. Patented Feb. 1, 1916.

Application filed March 30, 1915. Serial No. 18,120.

To all whom it may concern:

Be it known that I, OLIVER E. HARRIS, a citizen of the United States, residing at Abingdon, in the county of Knox and State 5 of Illinois, have invented certain new and useful Improvements in Rotary Churns, of which the following is a specification.

This invention relates to improvements in devices for mixing and disintegrating substances or compounds, such as churning, mixing machines or devices of various kinds and sizes, and has as one of its objects to improve the construction and increase the efficiency and utility of devices of this character.

Another object of the invention is to provide a simply constructed device, whereby the compound or material may be mixed or the particles disintegrated according to the 10 nature of the material or compound, and wherein the parts are readily separable for cleansing or repairs.

With these and other objects in view, the invention consists in certain novel features 15 of construction, as hereinafter shown and described and then specifically pointed out in the claim.

The improved device may be applied without material structural change to churning 20 and similar machines and to mixing or disintegrating devices of various forms, such as concrete mixers, cement mixers or the like, and it is not desired therefore to limit the invention in any manner in this respect.

The device is particularly applicable for use as a churn and for the purpose of illustration is shown thus applied; and in the drawings illustrative of the preferred embodiment of the invention, Figure 1 is a 25 sectional elevation. Fig. 2 is a transverse section on the line 2—2 of Fig. 1. Fig. 3 is a section on the line 3—3 of Fig. 1 of one of the supporting members and the blades of the outer mixer or disintegrating portion 30 of the device.

Corresponding and like parts are referred to in the following description and indicated in all the views of the accompanying drawings by the same reference characters.

The improved device will be erected in a suitable receptacle for the material to be mixed or disintegrated, such as a tub 10, when the device is applied to a churn. The bottom 11 of the tub 10 is provided with a 35 step 12 to receive the lower end 13 of a vertical shaft 14. The shaft 14 extends for a

considerable distance above the top of the tub and is provided at its upper end with a relatively small beveled pinion 15, the shaft 14 having a square upper terminal 16 to 40 detachably support the pinion, the object to be hereafter explained. The portion of the shaft within the tub 10 is likewise formed square, as shown at 17, and with a reduced lower portion or journal 18 between the 45 square portion 17 and the step engaging portion 13. Surrounding the shaft 14 is a sleeve 19, the latter being so located that it projects for a distance above the upper line of the tub and is formed with a square 50 bearing 20 to detachably receive a gear pinion 22. The tub 10 is provided with a top formed in two sections 23—24, the section 23 having a half bearing or collar 25 to engage partially around the sleeve 19 while the cover 24 is provided with a similar half 55 collar or bearing 26 to engage partially around the sleeve 19. The two members 25—26 entirely encompass the sleeve 19. The 60 lower end of the sleeve 19 is formed with a plurality of radial arms 27 which extend toward the walls of the tub. A collar 28 is mounted for rotation upon the bearing portion 18 of the shaft and is formed with a 65 plurality of radial arms 29 corresponding to the arms 27. Dasher blades 30 are connected to the terminals of the arms 27—29 and operate in close proximity to the inner 70 face of the tub. Mounted upon the square portion 17 of the shaft near its upper end 75 is a collar 31 having a plurality of radial arms 32 and mounted upon the square portion 17 of the shaft at its lower end is another collar 33, the latter bearing upon the collar 28, as shown. The collar 33 is provided with a plurality of radial arms 34, 80 similar to the arms 32. A plurality of slats or dasher members 35 are connected to the arms 32—34, as shown. The arms 32—34 are shorter than the arms 27—29 so that the 85 outermost slats 35 operate within the space between the dasher blades 30, as shown. The blades 30 are relatively thin and flat and the outer portion of the arms 27—28 are bent slightly so that the blades 30 operate 90 tangentially of the shaft 14 and of the tub 10, as illustrated in Figs. 2 and 3. By thus arranging the blades 30 to operate tangentially of the tub 10, the material which comes in contact with the blades is moved 95 outwardly toward the inner walls of the tub when the blades are moved in one direction,

- and the material moved toward the center of the tub when the blades are moved in the opposite direction, the object to be hereafter explained.
- 5 Connected to the tub 10 near its upper end is a supporting bracket including vertical members 36 and connected at 37 to the outer face of the tub. The members 36 are so arranged that the cover members 23—24 may 10 be readily removed and applied to the tub without interfering with the bracket members. The members 36 are connected by a transverse member 37' with bearings 38—39 above the portion 37', the bearings adapted 15 to receive an operating shaft 40 having an operating crank 41. At its inner end the shaft 40 is formed with a square bearing 42 to receive a beveled gear 43 which engages with the pinions 15—22, as shown. Extending 20 above the bearing 39 is a standard 44 having a flat upper bearing face 45 from which a pin 46 extends. Bearing upon the portion 45 of the standard is an arm 47 having an aperture to receive the pin 46 and 25 with a bearing 48 to receive an upwardly directed journal on the upper end of the shaft 14. A clamp screw 49 operates through the member 47 and into a threaded aperture in the bearing 45 to enable the member 47 to be 30 clamped in position upon the standard 44. By this means the upper end of the shaft 14 is firmly supported in position and may be rotated in either direction. By this arrangement, it will be obvious that when motion is 35 imparted to the shaft 40 by the crank 41, the gear 43 will be actuated and transmit motion in opposite directions to the pinions 15—22. The pinion 15 being attached to the shaft 14 will rotate the latter in the same direction, 40 while the pinion 22 being attached to the sleeve 19 will actuate the latter in the opposite direction. Thus the blades 30 will rotate in one direction while the slats 35 will be actuated in the opposite direction and 45 thus produce a rapid and thorough agitation of any material which may be deposited in the tub and thoroughly mixing and intermingling the same and, when employed as a churn, thoroughly and positively separating 50 the butter particles from the cream. The slats 35 being arranged radially of the shaft 14 mix the material which comes in contact therewith without appreciably moving it toward the outer walls of the receptacle or toward the shaft no matter in which direction 55 the shaft and the slats may be rotated, while the blades 30, being arranged tangentially of the tub and of the shaft, move the portion of

the material with which they come in contact outwardly or toward the walls of the receptacle when rotated in one direction and move the portion of the material with which they come in contact inwardly toward the shaft when the motion is reversed. By this means, the mixing is greatly accelerated by simply reversing the motion of the mechanism at intervals, as will be obvious.

When the device is to be dismembered or the parts separated, the cover members 23—24 are removed and the bolt 49 detached and the member 47 elevated upon its pin 46 to release the shaft 14. The pinion 15 and the shaft 14 may then be removed endwise leaving the pinion 22, wheel 43 and the sleeve 19, together with its attachments, and the sleeves 33 and their attachments, readily removable, as will be obvious. By this means the parts may be readily cleansed or repaired, or broken parts renewed without discarding the remainder of the device.

The sleeve 19, together with its arms 27, forms a spider-like device while the collar 28 and its arm 29 form another spider-like device. The collar 31 with its arms 32 likewise forms a separate spider-like device 85 while the collar 33 with its arms 34 forms another spider-like device, as illustrated more clearly in Figs. 2 and 3.

The improved device is simple in construction, can be inexpensively manufactured and applied for any purpose requiring the mixing or disintegrating of particles.

Having thus described the invention, what is claimed as new is:

In a churn, an inner dasher comprising a plurality of radial arms each carrying vertically spaced beaters, and an outer dasher comprising a plurality of radial arms directed obliquely to the longitudinal planes of the arms where they project beyond the arms of the inner dasher, and vertical blades secured to said obliquely directed portions, the sides of said blades extending in parallel relation, and means for reversibly rotating said dashers in opposite directions, whereby material is moved toward the center of the dasher when the same are rotated in one direction and moved away from the center when the dashers move in the other direction.

In testimony whereof I affix my signature 110 in presence of two witnesses.

OLIVER E. HARRIS. [I. S.]
